CODE-SENDING APPARATUS.

Application filed January 14, 1928. Serial No. 246,733.

This invention relates to apparatus for sending or transmitting code signals, the same having particular reference to devices of this nature in which a keyboard similar to a typewriter is employed, having a separate key for each code character so that a single depression of a key will send or transmit the corresponding code signal or signals.

One of the principal objects of the present invention is to provide a simple and improved apparatus for transmitting code signals over a relay circuit which includes a common wiper contact element adapted to be moved in a defined path and a character-forming contact element for each code character initially movable to an active position in the path of movement of the wiper contact together with electrical means for moving the wiper contact and electrical means for holding the character-forming contact element in its active position, said electrical means being included in a circuit having a switch operable by the movement of the character-forming contact element to its active position for closing the circuit and a second switch operable to open the circuit upon completion of the movement of the wiper contact over the character-forming contact for instantly breaking the circuit and allowing the parts to be returned to a normal position.

The invention further comprehends means for regulating or controlling the speed of movement of the wiper contact element during the transmission of the signals so as to conform to the speed at which the same may be received, while allowing for a quick or instantaneous return movement of the wiper contact to a normal position.

Other objects reside in the comparative simplicity of construction of the apparatus, the economy with which the same may be produced and the general efficiency derived therefrom.

With the above received and other objects in view, reference is had to the following description and accompanying drawings in which there is exhibited one example or embodiment of the invention, while the appended claims define the actual scope of the invention.

In the drawings—

Figure 1 is a diagrammatic view illustrating the apparatus;

Fig. 2 is a fragmentary perspective view

of a key illustrating particularly the character-forming contact element.

Referring to the drawings by characters of reference, 10 designates a relay circuit in which is included a common wiper contact element 11, suitably mounted for movement in a defined path, the same being illustrated as carried by rotary member 12 suitably mounted on a shaft 13. The member 12 is adapted for rotatory movement in one direction electrically by any suitable means, but, as illustrated, this means consists of a solenoid 14 having a core 15 which is movable in one direction when the solenoid is energized. The core 15 has attached thereto a cable 16 which is trained about a sheave 17 attached to the rotary member 12, the opposite end of the cable being connected to a coiled contractile spring 18. It thus follows that when the solenoid is energized the core will be moved upwardly to stretch the spring 18, and at the same time to turn the sheave 17 and the rotary member 12 in the direction indicated by the arrow. This causes the common wiper contact element 11 to be moved therewith in its defined path of movement. When the solenoid is de-energized it is obvious that the spring will exert a pull to move the core in an opposite direction and consequently rotate the member 12 and the wiper contact 11 in the opposite direction to a normal inactive position. The solenoid is arranged in a circuit 19 which also includes a normally open switch 20 having spring-pressed contact elements 21 and 22 which are normally separated by springs 23 and 24. The contact element 22 is provided with an actuator head 25.

The circuit further includes in series with the solenoid an electromagnet 26 and a second switch 27 having a stationary contact element 28 and a movable contact element 29, the latter being carried by the rotary member 12. Keys 30 fulcrumed at 31 are included in the relay circuit 10 and each key is provided with a code character-forming element or terminal 32 which are normally disposed out of the path of movement of the wiper contact element, but which are adapted to be selectively moved into the path of movement thereof by depression of a key-actuator lever 33 operatively connected to the key 30 in any suitable manner such as by a link 34. Each key is provided

with an insulated armature piece 35 which is designed to be attracted by the electromagnet 26. Each key is further provided with an insulated block 36 which is designed 5 to contact with the actuator head 25 of the contact element 22 of the switch 20.

In use, when the operator depresses the key-actuator lever 33, the key 30 connected therewith is swung upwardly in the direction 10 of the arrow into the defined path of movement of the wiper contact 11 which is common to all of the keys employed. The initial movement of the key 30 causes the block 36 to engage the actuator head 25 to force the contact 22 of the switch 20 into engagement with the contact 21. This simultaneously closes the circuit 19 to the electromagnet 26 and to the solenoid 14, causing the electromagnet to attract and 15 hold the key in its raised active position while the solenoid core 15 moves upwardly against the action of the spring 18 and turns or moves the common wiper contact over the face of the character-forming contact element 22. In order to regulate and prevent 20 a too rapid movement of the core 15 of the solenoid, and a corresponding excessive speed of movement of the wiper 11, the solenoid core 15 is suitably connected with a piston 25 or plunger 37 which is mounted in a closed cylinder 38 having open ports 39 at one end and having an adjustable outlet or pressure escape valve 40 adjacent the other end. In this way, adjustment of the escape valve 40 30 regulates the speed of movement of the solenoid core when the same is energized so as to control the speed of movement of the wiper contact 11, while when de-energized the solenoid core and wiper contact 35 may return to a normal position instantly 40 under the action of the spring 18. After the wiper contact is passed over the face of the character-forming contact element 32, the switch element 29 of the switch 27 moving 45 with the rotary member 12 will disengage the contact element 28 of the switch 27 and break the circuit 19, causing the magnet 26 and solenoid 14 to be de-energized. Instantly the springs 23 and 24 of the switch 50 20 function to swing the key 30 downwardly to its normal position out of the path of return movement of the wiper contact 11, at the same time breaking the circuit 19 at the switch 20. Immediately following the 55 breaking of the circuit 19 at the switch 20, the contact element 29 of the switch 27 will again engage the contact element 28 thereof and re-establish the circuit at this point until the next succeeding operation.

40. What is claimed is:

1. In an apparatus for transmitting code signals, a relay circuit including a common wiper contact element mounted for movement in a defined path and a character-forming contact element normally disposed

out of the path of movement of the wiper contact element and manually swingable into the path of movement thereof; a circuit including in series electrical means for moving the wiper contact element in one direction 70 and electrical means for holding the character-forming contact element when moved into the path of movement of the wiper contact element, a normally open switch in said circuit operable by the movement of the 75 character-forming contact element into the path of movement of the wiper contact element to close the circuit, and a second switch in said circuit operable to break said circuit after the wiper contact element has 80 completely moved over the character-forming contact element.

2. In an apparatus for transmitting code signals, a relay circuit including a common wiper contact element mounted for movement 85 in a defined path and a character-forming contact element normally disposed out of the path of movement of the wiper contact element and manually swingable into the path of movement thereof; a circuit including in 90 series electrical means for moving the wiper contact element in one direction and electrical means for holding the character-forming contact element when moved into the path of movement of the wiper contact element, a 95 normally open switch in said circuit operable by the movement of the character-forming contact element to close the circuit, a second switch in said circuit operable to break said circuit after the wiper contact 100 element has completely moved over the character-forming contact element, and means for returning and holding the wiper contact element and the character forming contact element in their respective normal 105 inactive positions.

3. An apparatus for transmitting code signals over a relay circuit, which includes in said relay circuit a common wiper contact element movable in a defined path, with 110 means for effecting the return of the same to and for holding the same in a normal inactive position, and a character-forming contact element for each code character normally disposed in an inactive position 115 out of the path of movement of the common wiper contact element and initially movable manually into the path of movement thereof, a circuit including in series energizable means for moving the wiper contact element over 120 the face of the character-forming contact element, and electro-magnetic means for holding the character-forming contact element in the path of movement of the wiper contact element when manually moved to 125 said position, and a normally open switch for closing the circuit to actuate the wiper contact element and to maintain the character-forming contact element in its active position.

4. An apparatus for transmitting code signals over a relay circuit, which includes in said relay circuit a common wiper contact element movable in a defined path, with means for effecting the return of the same to and for holding the same in a normal inactive position, and a character-forming contact element for each code character normally disposed in an inactive position out of the path of movement of the common wiper contact element and initially movable manually into the path of movement thereof, a circuit including in series energizable means for moving the wiper contact element over the face of the character-forming contact element and electro-magnetic means for holding the character-forming contact element in the path of movement of the wiper contact element when manually moved to said position, a normally open switch for closing the circuit to actuate the wiper contact element and to maintain the character-forming contact element in its active position, and a second switch in said circuit normally closing the same and operable to break said circuit when the wiper contact element has completely moved over the face of the character-forming contact element to permit the contact elements to move to a normal position.
5. In a code-sending apparatus, a relay circuit including a key for each code character, having a character-forming contact terminal and a common movable wiper contact element for said keys, a circuit including an electromagnet serving when energized to hold the key in an operative position, said circuit also including in series with the electro-magnet a solenoid operable when energized for actuating the movable wiper contact, and a key actuator lever for each key for initially moving the key to an active position in the path of movement of the wiper contact and for subsequently closing the circuit to the magnet and solenoid to hold the key in its active position and to move the wiper contact over the face of the character-forming contact terminal.
6. In a code-sending apparatus, a relay circuit including a key for each code character, having a character-forming contact terminal and a common movable wiper contact element for said keys, a circuit including an electromagnet serving when energized to hold the key in an operative position, said circuit also including in series with the electro-magnet a solenoid operable when energized for actuating the movable wiper contact, a key actuator lever for each key for initially moving the key to an active position in the path of movement of the wiper contact and for subsequently closing the circuit to the magnet and solenoid to hold the key in its active position and to move the wiper contact over the face of the character-forming contact terminal, and means operable by and upon completion of the movement of the wiper contact over the character-forming contact terminal of the key for breaking the circuit to de-energize the electromagnet and the solenoid, whereby to permit of the return movement of the wiper contact and the key to a normal inactive position.
7. In an apparatus for transmitting code signals over a relay circuit, which includes a wiper contact adapted for movement in a defined path and normally tensioned and maintained against movement, and a character-forming contact normally maintained in a position out of the path of movement of the wiper contact and manually movable into the path of movement thereof, a normally open circuit closed by movement of the character-forming contact element to an active position in the path of movement of the wiper contact, said circuit including means for holding the character-forming contact element in the active position, and means for moving the wiper contact over the face of the character-forming contact.
8. In an apparatus for transmitting code signals over a relay circuit, which includes a wiper contact adapted for movement in a defined path and normally tensioned and maintained against movement, and a character-forming contact normally maintained in a position out of the path of movement of the wiper contact and manually movable into the path of movement thereof, a normally open circuit closed by movement of the character-forming contact element to an active position in the path of movement of the wiper contact, said circuit including means for holding the character-forming contact element in the active position, means for moving the wiper contact over the face of the character-forming contact, and means for breaking the circuit after the movement of the wiper contact over the character-forming contact, said latter means being operative to re-establish the circuit at said point after the circuit is broken at the first-mentioned point by the return of the character-forming contact to a normal position.
9. In a code-sending apparatus, a relay circuit including a key for each code character having a character-forming contact terminal and a common movable wiper contact element for said keys, a circuit including an electromagnet serving when energized to hold the key in an operative position, said circuit also including in series with the electro-magnet a solenoid operable when energized for actuating the movable wiper contact, a key actuator lever for each key for initially moving the key to an active position in the path of movement of the wiper contact and for subsequently closing the circuit to the magnet and solenoid to hold the key in its active position and to move the wiper contact over the face of the character-forming contact terminal.

hold the key in its active position and to move the wiper contact over the face of the character-forming contact terminal, and means for regulating the speed of movement 5 of the wiper contact element in its active direction.

10. In a code-sending apparatus, a relay circuit including a key for each code character, having a character-forming contact terminal and a common movable wiper contact element for said keys, a circuit including an electro-magnet serving when energized to hold the key in an operative position, said circuit also including in series 15 with the electromagnet a solenoid operable when energized for actuating the movable wiper contact, a key actuator lever for each

key for initially moving the key to an active position in the path of movement of the wiper contact and for subsequently closing 20 the circuit to the magnet and solenoid to hold the key in its active position and to move the wiper contact over the face of the character-forming contact terminal, and means for regulating the speed of movement 25 of the wiper contact element in its active direction, said means comprising a cylinder, a piston in the cylinder connected with the solenoid core, and an adjustable outlet valve at one end of the solenoid. 30

Signed at city of Jersey City, in the county of Hudson and State of New Jersey, this 11th day of January, A. D. 1928.
